EXAMINER'S ROOM.

UNITED STATES PATENT OFFICE.

HORACE C. WILCOX, OF WEST MERIDEN, CONNECTICUT, ASSIGNOR TO THE
MERIDEN BRITANNIA COMPANY, OF SAME PLACE.

DESIGN FOR A TEA-SET.

Specification forming part of Design No. 6,218, dated October 22, 1872.

To all whom it may concern:

Be it known that I, HORACE C. WILCOX, of West Meriden, in the county of New Haven and State of Connecticut, have invented a new Design for Tea-Set; and I do hereby declare the following, when taken in connection with the accompanying photographic illustration, to be a full, clear, and exact description of the same, and which said illustration constitutes part of this specification and represents a side view.

This invention relates to a design for "tea-set" in plated or sterling ware; and consists in the peculiar configuration of the articles, as shown in the accompanying photographic illustration and as hereinafter described.

The set is usually composed of six pieces—tea-pot, coffee-pot, water-pot, slop-bowl, cream, and sugar bowl. The body of each piece is, in transverse section, of rectangular form, and vertically, commencing at the bottom, expanded in a curved line toward the top, where, turning at an angle, it is inclined or drawn in at the top to form the neck. The cover fitting the neck

rises with inclined sides to a deck form, terminating with an ornament, as denoted in the illustration. The pots are provided with a handle upon one side and a spout upon the other. The sugar-bowl with handles upon both sides. The slop-bowl has the same form of body but without the drawing-in portion of the top or cover. The cream has the same general features without the cover, and is provided with a handle and spout, all substantially as described.

In this design the handles and spout form no essential part, as different handles and different spouts may be supplied, the peculiar configuration of the body being the design.

I do not wish to be understood as confining myself to the combination of the several pieces mentioned; but

Claim as my invention—

The design for tea-set, as herein described and shown, as a whole or singly.

HORACE C. WILCOX.
